(57) **CLAIM**

I claim the ornamental design for a digital fishing net scale,
as shown and described.

DESCRIPTION

FIG. 1 is a perspective view showing the new design.

FIG. 2 is a front view showing the new design.

FIG. 3 is a rear view showing the new design.

FIG. 4 is a top view showing the new design.

FIG. 5 is a bottom view showing the new design; and,
FIG. 6 is a side view showing the new design with the
opposite side being a mirror image.

The broken lines depict environmental structure and are
included for the purpose of illustrating only and form no part
of the claimed design.

1 Claim, 3 Drawing Sheets

FIG. 5

FIG. 6
